UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

CORRUGATION IN HOPPER DOORS FOR RAILWAY CARS.

Application filed August 13, 1925. Serial No. 50,044.

The invention relates to a railway dump car having a "door" forming a part of the car for retaining the load therein, which door is provided with hinges adjacent one of its sides and is capable of being "dropped" or swung open so that the load in discharging slides or passes over the upper surface of the door. Any means of raising the door to the closed position and any means for locking and releasing the door may be employed with my device.

A door for this purpose must be very strong and durable because:

First: It is part of the floor of the car and as such must sustain the load as well as the impact blow when the car is in motion.

Second: The car is frequently loaded from chutes or tipples from a height of ten feet or more, causing the load to be dropped directly upon the doors.

Third: Clam shell buckets are frequently used to unload such cars and it is not uncommon for these buckets to rest upon and drag over the doors.

Fourth: When the door suddenly comes to rest after being dropped, it is not only subjected to a severe shock, but it must sustain the severe impact thrust of the load which, of course, follows the door.

Fifth: As the load is theoretically equally distributed, the door must be strong over its entire area and must be capable of transmitting the resulting strains to the car body without much deflection and no substantial distortion. Any bending of the door would cause a leak of the lading, especially of such fine material as sand, chats, etc. Any bending or warping might interfere with the complete closing and locking of the door.

As it costs as much to haul a ton of car as it does to haul a ton of paying freight, it is imperative that the car and any part thereof be as light as possible. Furthermore, the total weight of car and freight is determined by the strength of certain standard axles, so that the lighter the car the greater amount of freight a given car will be allowed to carry.

The advantages of my door are applicable to any door of a freight car over which the lading moves when being discharged from the car, such as drop bottom general service cars (used in the drawings) hopper cars,

swinging side doors or hopper bottom coal cars, etc.

An object of this invention is to provide a plate metal door with corrugations of particular contour that from their form are peculiarly adapted to meet the stresses and strains already described, and at the same time, to provide a very light and inexpensive door. The number of the corrugations will depend upon the number and location of the hinges.

In the drawings:
Fig. 1 shows a portion of a railway car with my device applied thereto.

Fig. 2 is a section on line 2—2 of Fig. 1.

Fig. 3 is a section on line 3—3 of Fig. 1.

Fig. 4 is an enlarged section through a corrugated portion of the plate.

A plurality of parallel strengthening corrugations 2 are formed in the metallic plate and terminated at their ends 3 into the plane of the plate so that the door has a flat marginal portion about its sides. The particular contour of the corrugation is illustrated in the large sectional view of Fig. 4. Each corrugation is formed with main walls 4 substantially perpendicular to the plane of the plate which are connected by curved portions 5. Each corrugation is wider than the distance 30 between parallel planes 31 and 32 drawn through the outermost parts of the corrugated plate. The greater the distance between the main walls 4, the greater the width of the connecting portions 5, and consequently, more metal is positioned away from the neutral axis 10—10 of the section, resulting in a higher section modulus, meaning, of course, a stronger corrugation, theoretically.

The connecting portion (5) is a (secondary) beam and must transmit the load imposed upon it to the main walls 4—4. In actual practice, a flat connecting portion will deflect and not perform its function if the main walls are spaced very far apart. My construction increases the capacity of the connecting member to transmit thrusts to the adjacent main walls and thereby permits the main walls to be spaced further apart, thus obtaining a higher section modulus, as stated above. The width of each corrugation is preferably constant throughout the major portion of its length.

The outwardly projecting portions 5—5 between the walls 4 act in the manner of an arch or bridge whereby the stresses are distributed throughout the outwardly projecting portions to the main walls.

The parts of the door 6 remaining (positioned) between the adjacent corrugations are preferably formed similar to the outwardly projecting portions 5—5 of the corrugation but project oppositely thereto, thus placing the neutral axis 10—10 of the corrugated plate midway between parallel planes drawn through the outermost parts of the corrugated plate.

It is preferable to position the corrugations parallel with the direction of the discharging cargo so that they will not interfere with its free movement. However, the corrugations may be positioned normal or at right angles to the direction of the moving cargo (or in fact, obliquely thereto), or the corrugations may be pressed entirely from either side of the plate (i. e., projecting upwardly or downwardly) or may be pressed partially from one side and partially from the other side of the plate, if desired. Any of such arrangements would come within the scope of this invention.

In my co-pending application Serial No. 50,043, filed August 13, 1925, I have disclosed and claimed a door having a plurality of parallel downwardly projecting embossments therein with flat places between some of the embossments and hinges parallel to the embossments and secured to the flat places, which structure is disclosed but not claimed in this application.

What I claim is:

1. In combination with the other elements of a railway dump car, a door supported by hinges adjacent one side made of a metallic plate formed with integral corrugations, main walls and curved arched portions connecting said main walls, the width of each corrugation being greater than the distance between parallel planes drawn through the outermost parts of the corrugated plate.

2. In combination with the other elements of a railway dump car, a door supported by hinges adjacent one side made of a metallic plate formed with integral corrugations of constant width throughout the major portion of their length, having main walls and curved arched portions connecting said main walls, the width of each corrugation being greater than the distance between parallel planes drawn through the outermost parts of the corrugated plate.

3. In combination with the other elements of a railway dump car, a door supported by hinges adjacent one side made of a metallic plate formed with integral corrugations merged into the plate at their ends, main walls and curved arched portions connecting said main walls, the width of each corruga-

tion being greater than the distance between parallel planes drawn through the outermost parts of the corrugated plate.

4. In combination with the other elements of a railway dump car, a door supported by 70 hinges adjacent one side made of a metallic plate formed with integral corrugations spaced apart distances equal to their width, main walls and curved arched portions connecting said main walls, the width of each corrugation being greater than the distance between parallel planes drawn through the 75 outermost parts of the corrugated plate.

5. In combination with the other elements of a railway dump car, a door supported by 80 hinges adjacent one side made of a metallic plate formed with integral corrugations of constant width throughout the major portion of their length and spaced apart distances equal to their width and merged into the 85 plate at their ends, said corrugations having main walls and curved arched portions connecting said main walls, the width of each corrugation being greater than the distance between parallel planes drawn through the 90 outermost parts of the corrugated plate.

6. In combination with the other elements of a railway dump car, a door supported by 95 hinges adjacent one side made of a metallic plate formed with integral corrugations, main walls and curved portions connecting said main walls, the width of each corrugation being greater than the distance between parallel planes drawn through the outermost parts of the corrugated plate and the 100 spaces between said corrugations arched in the opposite direction to said arched portions.

7. In combination with the other elements of a railway dump car, a door supported by 105 hinges adjacent one side made of a metallic plate formed with integral corrugations of constant width throughout the major portion of their length having main walls and curved arched portions connecting said main walls, the width of each corrugation being 110 greater than the distance between parallel planes drawn through the outermost parts of the corrugated plate and the spaces between said corrugations arched in the opposite direction to said arched portions.

8. In combination with the other elements of a railway dump car, a door supported by 115 hinges adjacent one side made of a metallic plate formed with integral corrugations merged into the plate at their ends, main walls and curved arched portions connecting said main walls, the width of each corrugation being greater than the distance between parallel planes drawn through the outermost parts of the corrugated plate and the 120 spaces between said corrugations arched in the opposite direction to said arched portions.

9. In combination with the other elements of a railway dump car, a door supported by 125

hinges adjacent one side made of a metallic plate formed with integral corrugations spaced apart distances equal to their width, main walls and curved arched portions connecting said main walls, the width of each corrugation being greater than the distance between parallel planes drawn through the outermost parts of the corrugated plate and the spaces between said corrugations arched 5 in the opposite direction to said arched portions.

10. In combination with the other elements of a railway dump car, a door supported by hinges adjacent one side made of a metallic

plate formed with integral corrugations of 15 constant width throughout the major portion of their length and spaced apart distances equal to their width and merged into the plate at their ends said corrugations having main walls and curved arched portions 20 connecting said main walls, the width of each corrugation being greater than the distance between parallel planes drawn through the outermost parts of the corrugated plates and the spaces between said 25 corrugations arched in the opposite direction to said arched portions.

VINTON E. SISSON.
